UNITED STATES PATENT OFFICE.

MANSELL ALLAN DAVIS, OF WAUKEGAN, ILLINOIS.

BED-BOTTOM FABRIC.

Application filed September 20, 1927. Serial No. 220,681.

The purpose of this invention is to provide a wire mattress fabric, especially adapted for folding cots, which will have a limited amount of resiliency in its strands, permitting the fabric to be stretched endwise over the cot frame, avoiding the necessity for springs, and which will have smooth finished side edges. A further purpose of the invention is to provide end bars of light construction and having means whereby the fabric may be securely and inexpensively connected to it, said end bars serving as a means for detachably connecting the fabric to the cot frame.

15 The fabric of the present application is shown in my co-pending application, Serial Number 75,995, filed December 17, 1925, but not claimed therein.

20 In the accompanying drawing, Fig. 1 is a top plan view of the fabric and end bars, the side rails of the cot frame being also shown;

25 Fig. 2 is an enlarged detail view of a portion of the fabric; and,

Fig. 3 is a section on the line 3—3 of Fig. 2.

The fabric comprises a plurality of similar wire strands, *a*, *b*, *c*, *d*, etc., each bent to form a succession of relatively narrow loops, opening alternately in opposite directions, the loops of the strand *a* being indicated at 1^a and 2^a; those of the strand *b* being indicated at 1^b and 2^b, and those of the strand *c* being indicated at 1^c and 2^c. The sides 4 of the loops of each strand are parallel, and the closed ends 5 of the loops are substantially at right angles to the sides. In assembling the strands to form the fabric, the closed ends of the loops of one strand, as *b*, are hingedly connected to the closed ends of two adjacent strands, as *a* and *c*, by metal clips 6. Thus, when the closed ends of the loops of several strands are connected together by the hinge clips, the open ends of the intermediate loops, as 1^b, 2^c, and 1^a, 2^b, will meet and these meeting loops form larger closed loops *h* of rectangular shape. The straight parallel sides of the loops stiffen the fabric lengthwise, but the fabric can stretch lengthwise to some extent because each right-angled loop end can yield to a limited extent when tension is put upon the fabric in the direction of its length. This avoids the necessity for connecting the fabric by springs to the end bars of the mattress. In order to give a smooth finish to the side edges of the fabric and to secure

the ends of the several strands, the terminals of the strands at the edges of the fabric are bent to form closed loops, as 3^a, 3^b, and 3^c. Thus, the side 4^a of the loop 3^a has its end 60 portion 5^a turned backwardly and thence upwardly against the side 4^b of the loop to which it is secured by a clip 7. Similarly, the side 4^a of the loop 3^b has its end portion 5^a turned backwardly and secured by a clip to the side 65 4^b of the loop. The loops 3^a and 3^b are hingedly connected by a clip 6^a, and the loops 3^b and 3^c, which are similarly formed, are connected by a clip 6^b. The end loops of all 70 of the strands are alike, and the end loops of adjacent strands are hingedly connected together by clips, as shown. Thus, the ends of the wires are all turned backwardly at the edges of the fabric to form closed loops and are secured by clips. Strong end loops are 75 thus provided, the edge of the fabric is smooth, and the ends of the strands are held so that they cannot catch in the bed covers, or scratch the person handling the fabric.

79 The finished fabric is secured to light metal end bars 10, each having a series of tongues 8 punched out from the body of the bar. The loops at the ends of the fabric are hooked over these tongues and the tongues are then depressed so that the fabric becomes securely 85 fastened to the end bars, as shown in the drawing.

What I claim is:

1. A mattress fabric for camping cots, comprising a plurality of wire strands each 90 bent to form a continuous series of similar loops, opening alternately in opposite directions, the sides of the loops being parallel and the ends of the loops being substantially at right angles to the sides, metal clips hingedly connecting the ends of alternate loops in each strand with the ends of alternate loops in an adjacent strand, the terminals of each strand being bent backwardly, closing the end loops of the strand, and a clip hingedly connecting the backwardly bent portion of each end loop to the similar portion of an end loop in an adjacent strand. 95

2. A mattress fabric for camping cots, comprising a plurality of wire strands each 105 bent to form a continuous series of similar loops, opening alternately in opposite directions, the sides of the loops being parallel and the ends of the loops being substantially at right angles to the sides, metal clips hingedly connecting the ends of alternate loops in each strand with the ends of alternate 110

- loops in an adjacent strand, the terminals of each strand being bent backwardly, closing the end loops of the strand, and thence parallel with the inner sides of said end loops, 5 clips securing the ends of the strands to said inner sides, and a clip hingedly connecting the backwardly bent portion of each end loop to the similar portion of an end loop in an adjacent strand.
- 10 3. A mattress fabric for camping cots, comprising a plurality of wire strands each bent to form a continuous series of similar loops, opening alternately in opposite directions, the sides of the loops being parallel and 15 the ends of the loops being substantially at right angles to the sides, metal clips hingedly connecting the ends of alternate loops in each strand with the ends of alternate loops in an adjacent strand, the terminals of each strand being bent backwardly, closing the end loops 20 of the strand, and thence parallel with the inner sides of said end loops, the ends of the

strands being secured to said inner sides, and a clip hingedly connecting the backwardly bent portion of each end loop to the similar portion of an end loop in an adjacent strand. 25

4. A mattress fabric for camping cots, comprising a plurality of wire strands each bent to form a continuous series of similar loops, opening alternately in opposite directions, means hingedly connecting the ends of alternate loops in each strand with the ends of alternate loops in an adjacent strand, the terminals of each strand being bent backwardly, closing the end loops of the strand, the ends of the strands being secured to the inner sides of the end loops, and means hingedly connecting the backwardly bent portion of each end loop to the similar portion of an end loop in an adjacent strand. 30 35 40

In testimony whereof I hereunto affix my signature.

MANSELL ALLAN DAVIS.
